UNITED STATES PATENT OFFICE.

WILLIAM HENRY RICHARDSON, OF THEBARTON, AND FREDERICK LIND-SAY WOODS, OF BROMPTON, SOUTH AUSTRALIA, AUSTRALIA.

GOVERNOR FOR MARINE ENGINES.

No. 839,644.

Specification of Letters Patent.

Patented Dec. 25, 1906.

Application filed August 8, 1905. Serial No. 273,272.

To all whom it may concern:

Be it known that we, WILLIAM HENRY RICHARDSON, residing at George street, Thebarton, and FREDERICK LINDSAY Woods, residing at East street, Brompton, in the State of South Australia, Commonwealth of Australia, subjects of the King of Great Britain, have invented new and useful Improvements in Automatic Regulators for Gravitation Governors for Marine Engines, of which the following is a specification.

Our invention relates to automatic governors for marine engines, and more particularly to a regulator for governing the movement of the pendulum-weight in governors of the gravitation type.

In gravitation-governors for marine engines as at present devised the movement of the vessel causes an immediate adjustment of the throttle-valve; but it has been found in practice that the continual variation of the valve has resulted in loss of efficiency, owing to the frequency with which the steam is cut off while the propeller is still doing useful work in the water.

The object of our invention is to so regulate the movement of a pendulum-weight that it only becomes effective when the vessel exceeds a predetermined angle of inclination or pitch, the object of the invention being attained by a secondary weight-gear and a system of locking and releasing levers which control the main weight.

We will now proceed to describe our invention by aid of the accompanying illustrations, in which—

Figure 1 is a side elevation of the improved governor, the parts being shown slightly in perspective. Fig. 2 is a part side view of same and is likewise in perspective.

In both illustrations similar letters of reference are used to denote similar or corresponding parts wherever they occur.

We will first describe the principal features already known in pendulum-governors. In this respect, *a* is a foundation-plate, to which the standards *b* are fastened, upon the upper end of which standards main bearings *c* are provided and are fitted with suitable lubricators *d*.

e is the trunnion, the ends of which are set in the main bearings *c*. The trunnion sup-

ports the weight-carriers *f*, upon which the pendulum weight or weights *g* are mounted.

h is a cross-arm rigidly fastened to the trunnion, on one end of which the counterpoise-weight *j* is fastened, the opposite end being connected, by means of the main connecting-rod *k*, to an oscillating valve-lever *l*, which in turn is connected by any convenient means to an engine valve or throttle. (Not shown in the illustrations.)

The foregoing several parts or modifications thereof are already well known in connection with gravitation-governors for marine engines.

Coming now more particularly to the details of our present invention, we provide a weighted regulator-lever *m*, which is mounted on a bearing *n* and is free to move backward and forward within a guide *o*, above which a graduated quadrant *p* is arranged, the end of the regulator-lever terminating with a pointer or index-finger which lies adjacent to the graduations on the quadrant.

q is an adjustment-screw, the end of which, either with or without a terminal block, affords a ready means for adjusting the position of the regulator-lever and limiting its travel, thereby allowing it to be set in a more or less vertical position, according to requirements. Upon the shaft which carries the weighted regulator-lever a double-ended lever *r* is rigidly fastened, but is capable of being set at any convenient angle.

The upper end of the lever is designed to engage with a locking-pawl or trigger *s*, which falls by gravitation or may be spring-governed. On the lower end of the lever a roller-bearing or its equivalent is mounted and is set in such a position that it engages the trip-lever *t*, to which a small connecting-rod *u* is fastened.

This connecting-rod is attached to a main locking-pawl *v*, which is designed to engage a suitable catch *w*, mounted upon the main weight *g*, above mentioned. The main locking-pawl *v* is mounted upon a fixed portion of the frame, as also is the trip-lever *t* and the weighted regulator-lever *m*; but the locking-pawl *s* is mounted upon the swinging weight-carrier *f* and moves in unison with the main weight.

For convenience of explanation the movement of the main weight is referred to figuratively, but actu-

ally it is the fixed portions of the appliance which move in unison with the vessel, the main weight when disengaged being always stationary and in a vertical position, as will be well understood.

The operation of our invention is as follows: Under ordinary circumstances the main weight, following the laws of gravitation, would relatively swing forward in the direction of the arrow shown in Fig. 1 when the vessel pitches forward, although actually the weight remains vertical and the other portions are out of plumb, as above mentioned, but according to our invention is retained in relatively vertical position by the main locking-pawl *b* until the pitch of the vessel reaches such an angle that the weighted regulator-lever *m* travels by gravitation across the dead-center of the guide *o* in the direction of the adjacent arrow-head. This movement of the weighted regulator-lever results in a corresponding movement of the double-ended lever *r*, the lower end of which then impinges upon the trip-lever *t* and causes the free end of same to be deflected downward, thus forcing the small connecting-rod *u* upward, so that said rod in turn lifts the main locking-pawl *v*, thereby disengaging the main weight and allowing it to assume a vertical position by gravitation—that is to say, it becomes relatively out of plumb with the other parts, as previously indicated. During the movement of the weight the upper portion of the double-ended lever *r* glides without interference along the under side of the locking-pawl *s*; but as soon as the weight normally begins to recede to its original position (actually the weight does not move) the upper end of the double-ended lever comes into contact with the locking-pawl *s*, which is raised by means of the tail portion, which comes into contact with a fixed bar adjacent thereto, and continuing its relative traverse pulls the weighted regulator-lever back again to its former position across the dead-center of the guide-bar and simultaneously causes the pressure to be released from the outer end of the trip-lever *t*, so that the connecting-rod and main locking-pawl again fall downward to their original position, at the same time engaging the catch *w*, which locks the main weight.

From the foregoing descriptive matter it will readily be understood that no displacement of the main weight can take place until the pitch of the vessel is sufficient to throw the weighted regulator-lever across the dead-center line of gravitation, and it is only after this has been done that the main weight becomes free, and operating upon the cross-arm, main connecting-rod, and other levers connected

with an engine-valve, that the regulation of the steam can take place, and it will likewise be seen that the position or set of the weighted regulator-lever can be adjusted by the adjustment-screw *g* to suit the requirements of each case, it being possible to afford a very delicate adjustment by setting the regulator-lever in an almost vertical position, so that a very slight movement will throw it across the dead-center, or by allowing it to lie at a greater angle, so that a greater pitch of the vessel will be necessary to move it.

Having now particularly described and ascertained the nature of our said invention and the manner in which it is to be performed, we declare that what we claim is—

1. In automatic governors for marine engines a weighted regulator-lever mounted upon a fixed portion of the frame, a double-ended lever connected therewith, a locking-pawl attached to a portion of the mechanism which moves in unison with a pendulum-weight, said locking-pawl being arranged to engage the upper portion of the double-ended lever, a trip-lever pivotally mounted to a fixed portion of the frame so that it may be operated by the lower portion of the double-ended lever, a small connecting-rod attached to the outer end of the trip-lever and a main locking-pawl connected therewith said locking-pawl being arranged to engage with a catch connected with the pendulum-weight so that said pendulum-weight may be released by the operation of the regulator-lever or engaged by the combined action of the pendulum-weight and locking-lever gear substantially as described.

2. In automatic governors for marine engines a graduated quadrant, an adjustment-screw and a guide-plate arranged in combination with a weighted regulator-lever for setting or adjusting the angle of inclination or pitch at which it is desired that the regulator-lever shall become operative.

3. In automatic governors for marine engines a regulator-lever, an adjustment-screw a cross-lever and a locking-pawl, a trip-lever, connecting-rod and main locking-pawl in combination with a pendulum-weight having a locking-catch thereon, a cross-arm, main connecting-rod and valve-lever arranged together substantially as specified as a combination of parts.

In testimony whereof we have signed our names to this specification in the presence of two subscribing witnesses.

WILLIAM HENRY RICHARDSON.
FREDERICK LINDSAY WOODS.
